AGITATING AND DISPENSING UNIT

Henry A. De Phillips, Nutley, N. J., and Harold J. Vath, Westhaven, Conn.; said Vath assignor to said De Phillips

Application July 27, 1946, Serial No. 686,797

10 Claims. (Cl. 259—4)

1

This invention relates to an agitating and dispensing unit and, particularly, to a combined agitating and eduction unit for use in connection with drums, vats and the like, the contents of which are liquid materials such as paints, lacquers and varnishes.

In the paint, lacquer and varnish manufacturing and spraying art, for example, where batches of paint, lacquer and/or varnish are to be supplied through a spray gun unit, it has been customary to feed such material to the spray unit by gravity, or by cup or by a pressure tank unit where it is necessary to utilize a compressor unit for feeding the material under a pressure of about 75 to 80 lbs. per sq. in.

In order to improve upon the above features of the art, it is an object of the present invention to provide a compact unit for agitating paint, lacquer, varnish or like mixtures for thoroughly distributing the solid particles throughout the vehicle, and ultimately force the eduction of the agitated mixture from the container in which agitated so as to be used subsequently for spraying and coating purposes.

It is another object of this invention to provide a unit for connection with containers for agitating and evacuating the contents from said drums and containers under pressure.

A further object of the invention is to provide an easily operable and attachable compressed air conducting unit in combination with a container for agitating and educting the contents of the container under the influence of air pressure in the container.

Another object of the invention is to provide means of a unitary construction combined with a container for initially agitating the contents, and then forcing said contents from the container by means of air pressure regulably passed through the means into the container so as to permit subsequent use of the educted contents from the container for spraying and similar purposes.

Other objects and features of this invention will become apparent from the following description taken in connection with the accompanying drawings in which:

Fig. 1 is an elevational partly sectional view of a preferred embodiment of the invention, as used; and

Fig. 2 is a section of a detail taken on line 2—2 of Fig. 1.

Referring now to the drawings in which like reference characters denote like parts throughout, a bung 10 provided with an externally threaded portion 11 is adapted for connection

with the internally threaded opening 12 of a drum or keg 13. It is to be noted that said drum is preferably of the heavy gage type having a reinforced eye-wash, welded and crimped cap on top, said drum being used in the paint and like industries whereby bulk quantities of such materials are transported.

Said bung 10 is provided with three openings, namely, 14, 15 and 16, for connection therewith of certain parts as will be hereinafter more fully described. In connection with opening 14 of said bung is a tubular member 17 extending to the bottom of the interior of the drum. Projecting outwardly of the bung and upwardly from the tubular member 17 is a tube 18 connected to a two-way valve 19. Said valve is also connected to an air intake regulator 20 which, in turn, is adapted to be connected at its end 21 with a source of air pressure, not shown. The air regulator is further provided with a pressure gage 22 connected thereto in the usual manner, as shown, so as to indicate the pressure of the air passing through the regulator 20. The air flow, furthermore, may be easily controlled by means of manually operable member 23 in said regulator 20.

Said valve 19 is further connected, as shown, at right angles to tube 18 and in line with regulator 20 to a safety valve 24 which is also connected by means of an extension tube 25 to opening 15 of said bung 10. Said valve 24 may be adjusted so as to permit the escape of excess air under pressure when said pressure in the container 13 exceeds, for example, 5 to 10 lbs.

As shown in Fig. 2, it will be noted that the housing for valve 19 is provided with three passages, 26, 27 and 28 respectively, while the valve member itself is provided with two passages, namely, 29 which extends the full diameter of the valve, and 30 which meets with and is set at right angles to said passage 29. It is to be further noted that said tube 25 merely extends into the opening 15 of the bung in contrast to the tubular member 17 which extends to the bottom of the container 13.

Mounted in opening 16 of bung 10 is an eduction tubular member 31 which extends to the bottom of said container 13. Extending upwardly and outwardly from said member 31 is a tube 32 containing a manually operable valve 33 adapted to control the flow therethrough of material 34, such as paint or lacquer, in the container 13. Said tube 32, it will be noted, is adapted for connection to a feed line, not shown, for subsequent use of the contents 34 being forced out of said drum 13.

In order to operate the device of the present invention, as shown, with drum 13, the material contents 34 are initially agitated so as to obtain a uniform mixture before it is forced or educted from the drum 13. Valve 33 is turned to the closed position, as shown in Fig. 1, and valve 19 is in the position, as shown in Figs. 1 and 2, whereby air entering through the regulator 20 by means of opening 21 passes through passages 26, 30 and 29 and through passage 27 into the member 17 to the bottom of the container 13 whereupon air bubbles disseminating through the material 34 of the drum agitate and stir the solid particles of the mixture to uniformly distribute them throughout the total mass of the material 34 in the container. Any excess pressure that is built up in the drum escapes through outlet 35 of safety valve 24. This operation is continued until agitation of the solid particles throughout the material 34 is completed, whereupon both valves 19 and 33 are turned 90° to the left in the drawing with the respective handles in horizontal position whereupon the air entering through passage 26 passes completely through passage 29 into tube 25 and in turn to the air space above material 34 in container 13. The pressure in said container is built up sufficiently to force the material 34 upwardly through tubular member 31 and through valve 33 to a connecting unit, not shown, which leads to a spray gun where the material 34 is to be further used.

From the foregoing description and accompanying drawings, it will be noted that a simply operated, compact, economic and highly efficient unit is provided which can be easily attached to drums of the type characteristic of the paint, lacquer and varnish arts and functions with little or no trouble and at a minimum of expense. Furthermore, this device, as shown, is safe and easy to handle.

The invention furthermore provides for automatically shutting off the feed line when agitating the ingredients in material 34 and vice versa. The air pressure, furthermore, is controlled on the different lines by means of the dual valve control unit for agitating and feeding the agitated contents of the drum. Furthermore, the bubble mixer is controlled by the safety outlet valve 24. It will be noted that, when the device in connection with drum 13 is not in use, the air pressure remaining in the drum may be released in various ways, preferably by inserting a release petcock or valve in the bung of the drum, by releasing the connection in the safety valve 24 or by relieving the air pressure by continuously operating the spray gun nozzle.

While a preferred embodiment of the invention has been described in connection with the accompanying drawings, various changes or modifications as to form, arrangement of parts and structure may be made without departing from the spirit and scope of the claims as contained herein.

We claim:

1. Apparatus for connection to a container for paints, lacquers and the like, adapted for agitating and expelling the contents therefrom under pressure, comprising a closure member for the container having an air inflow regulator for connection with a source of air, a gage in connection with said regulator, a tube member connected to and extending through the closure member to the bottom of said container, operable valve means interconnecting said regulator and the

tube member adapted to direct the flow of air therethrough into the tube and agitate the contents of the container, a by-pass safety unit in connection with said closure member and the valve, having conduit means extending from the closure member adapted to permit the escape of excess air under pressure from the container through the conduit means and the unit during the agitation of the contents in the container, and a valve controlled tube member extending through the closure member into the container adapted to educt the contents of the container when the first noted valve is actuated accordingly.

15 2. A removable unit for connection with a container for paints, lacquers and the like, adapted to agitate and force the contents therefrom, comprising a closure member for mounting on the container, an air flow regulator, a pressure gage connected to said regulator, means extending through the closure member into the container and toward the bottom of the container, valve means interconnecting said regulator and extending means to permit the flow of air therethrough into the container and agitate the contents thereof, a by-pass safety unit having a conduit in connection with said closure member and the valve adapted to permit the escape of excess air under pressure from the container through said conduit during the agitation of the contents in the container and permit the flow of air therethrough into the container to force the contents therefrom, and valve controlled means extending through the closure member into the container adapted to educt the contents of the container when the first noted valve is actuated whereby the air is by-passed through the safety unit into the area above the contents.

3. A removable unit for connection with a container adapted for agitating and forcing the contents therefrom, comprising closure means attachable to the container having an air pressure regulator for connection with a source of air, tubular means extending through the closure means into the container and toward the bottom of the container, selectively operated valve means interconnecting said regulator and tubular means for directing the flow of air into the contents and agitate the same, a by-pass safety unit having separately disposed conduits, one in connection with said closure member and the other with the valve, adapted to permit the escape of excess air under pressure from the container during the agitation of the contents in the container, and a valve controlled tube member extending through the member into the container adapted to educt the contents of the container when the first noted valve is actuated accordingly, to permit the air under pressure to pass to the top of the contents in the container and forces the contents from the container.

4. The combination with a drum for paints, lacquers and the like, of a removable closure member containing a plurality of separate, independently operable tubular members extending short of the bottom of the interior of said container, safety means connected to the closure member and in communication with the container adapted to permit escape of excess air under pressure from the container, air pressure regulable means in connection with one of the tubular members adapted to permit agitation of the contents of the container, a valve member in connection with the second tubular member adapted to permit the eduction of the con-

tents through said member when said valve is accordingly adjusted, and conduit means having a valve interconnectibly disposed intermediate the air pressure means and safety means adapted to selectively utilize the air passing therethrough for agitating the contents of the container and for forcing the contents from said container.

5. The combination with a drum, of a removable bung containing a plurality of separate, independently operable tubular members extending short of the bottom of the interior of said container, pressure regulable means in connection with one of the members in the bung and adapted to permit flow of air therethrough to agitate the contents in the container, a bypass unit in connection with the bung at one end, and in right angled connection with the pressure regulable means, and a valve member in connection with the pressure regulable means intermediate the tubular member and the bypass unit adapted to permit the eduction of the contents through the other tubular member when said valve is accordingly adjusted.

6. Apparatus for connection with a container for paints, lacquers and the like adapted to agitate and expel the liquid contents from said container, comprising a closure member adapted to seal an opening in the container, a plurality of separate conduits extending from the member to the bottom of the container, a combined safety blow off or by-pass unit in connection with the member, adjustable means interconnecting one of the conduits with the blow off unit for alternately directing the flow of air under pressure into the tube and blow off unit, and manually operable means in connection with the other tubular member adapted to permit the eduction of the contents through said member when the air is directed through the blow off unit.

7. Apparatus in combination with a container for lacquers, paints and the like, comprising a two-way air valve unit, a removable sealing member for the container, tubular means in connection with the valve unit, mounted onto the sealing member and extending to the bottom of the container, a safety blow-off unit connected to said sealing member and communicating with said valve unit, and another valve controlled tubular means extending through the sealing member into the bottom of the container adapted to conduct the contents from the container when air is by-passed through the valve into the blow-off unit and forced onto the surface of the contents in the container.

8. In combination with a container for lacquers, paints, enamels and the like, agitating and blowing apparatus containing pressure regulating means for connection with a source of air supply, an air conduit extending into the interior of the container, a two-way valve interconnecting the regulator means and the air

conduit for agitating the contents of the container, a blow-off unit in communication with the container and the valve, said valve being disposed between the regulating means and the blow-off unit whereby the contents after being agitated are forced through said valve controlled unit, and another valve controlled conduit extending to the bottom of the container adapted to permit flow of the contents of the container therethrough when the container is to be emptied.

9. In combination with a movable container for paints, lacquers and the like, apparatus comprising air flow regulating means for connection with a source of air supply, an air conduit communicating with the regulating means and extending into the container, a blow-off unit in connection with the container, a two-way valve interconnecting the regulator means and the blow-off and adapted to permit selective flow of air through the air conduit and the blow-off unit into the container, and an exit conduit extending to the bottom of the container adapted to exhaust the contents of the container when air under pressure is forced into the container via the blow-off unit.

10. Removable apparatus for use in combination with a container for paints, lacquers, and the like, comprising a bung, a plurality of separate independently operable tubular members extending from the bung to the bottom of the container, a by-pass safety unit having a tube connected to the bung for communicating with the interior of the container, multiple way valve means interconnecting one of the tubular members and the safety unit, pressure regulable means in connection with said valve means adapted to permit the selective flow of air therethrough into said last named tubular member to agitate the contents of the container and upon selective operation of the multiple way valve means to by-pass air through the safety unit connection into the container to exert pressure against the surface of the contents, and another valve member in connection with the other tubular member to permit eduction of the contents in the container when air is passed into the container through the safety unit tube.
